UNITED STATES PATENT OFFICE.

ARTHUR SNOW, OF CHAMBERSBURG, ASSIGNOR OF ONE-HALF TO JOSEPH S. MAYER, OF WHITE HILL, NEW JERSEY.

POTTERY-KILN.

SPECIFICATION forming part of Letters Patent No. 394,622, dated December 18, 1888.

Application filed September 20, 1887. Serial No. 250,243. (No model.)

To all whom it may concern:

Be it known that I, ARTHUR SNOW, a citizen of the United States, residing at Chambersburg, in the county of Mercier and State 5 of New Jersey, have invented a new and useful Improvement in Downdraft Pottery-Kilns, of which the following is a specification.

My invention relates to an improvement in pottery-kilns, wherein the heat from the fires 10 after filling the oven of the kiln impinges against the crown and is deflected and drawn downward by a special arrangement of flues. The division of the space under the oven-floor of downdraft kilns into an upper and 15 a lower draft-chamber has heretofore been formed by the very expensive process of springing an arch between them.

One object of my invention is by a novel construction of the lower chamber to super- 20 sed the use of this arch by simpler and less expensive construction. Secondly, the down- draft kilns as heretofore constructed return the draft to the uptake either by an annular flue built within the oven or by external 25 chimneys, sometimes one of these latter being employed, but never more than two of them. The objection to the annular flue is the great expense entailed in construction, the reduction of the oven-space of the kiln 30 caused by its insertion therein, and the enormous expense entailed in its application to changing the old direct-draft kiln into the modern downdraft kiln; also reducing the oven-space in the transformation. The ob- 35 jection to either one or two external chimneys is, that the central portion of the kiln- oven between the two chimneys (owing to the fact that draft inevitably takes the shortest cut in its exit) receives more than its. 40 quota of heat, while the space on each side will have its quota proportionately lessened, resulting in an unequal and detrimental burn- ing of the ware.

The object of the second part of my inven- 45 tion is to obviate these defects.

The first part of my invention consists in dividing the lower or return draft-chamber into two annular compartments, whereby an intermediate wall is provided to support the 50 properly-shaped fire-clay blocks of which I

form the division between the upper and lower draft-chambers.

The second part of my invention consists in connecting my annular return-flues with three or more external chimneys, to insure a 55 more equal distribution of heat in the kiln- oven, three being shown in the drawings accompanying this specification for convenience of illustration.

I attain these objects by the mechanism 60 illustrated in the accompanying drawings, in which—

Figure 1 is a vertical section of my im- 65 proved kiln, taken on line 1 2 3. Fig. 2 is a transverse section of the kiln, taken on the line 4 5 of Fig. 1, showing the construction of my return-draft chamber.

Similar letters refer to similar parts throughout the several views.

A, Fig. 1, is the oven of the kiln, wherein 70 the saggers containing ware to be burned are placed.

B is one of ten similar fires used for heat- 75 ing oven A.

B' is one of ten similar flues through which 75 the heat from fire B passes into the oven A adjacent to its periphery.

B² is a flue common to the ten fires B, through which the heat from fires passes into the central portion of oven A. It is connected 80 with fires by flue B³.

B⁴ is the lower return-draft chamber di- 85 vided into flues F F' by the annular wall E³, inserted therein as a support for the plates of fire-brick which form the division between the upper and lower draft-chambers.

C is a sight-hole for observing the progress 85 of fire B.

D is a damper operated from the outside 90 of kiln. Its object is to allow the smoke to escape from the oven A until the fires are fairly started, when it is closed and the combustion is carried on through the downdraft flues and chimneys.

E E' E² are three downdraft flues in free 95 connection with the two annular feeder-flues F F', and connected with oven A by flues E⁴ E⁵ E⁶.

E³ is an annular wall dividing flues F F', and also supporting the plates which form 100

the division between the upper chamber, B³, and lower flues, E E' E² F F'.

F² F³ F⁴ are three chimneys connecting the three flues E E' E² with the uptake x.

5 The operation of my improved kiln is substantially as follows: First, raise damper D, then start all the fires; when, by looking through the sight-hole C, you perceive that the oven A is free from smoke, drop the damper D. The heat now entering the oven A by flues B' B² will be deflected by the oven-crown and drawn downward by ten sets of concen-

tric flues, E⁴ E⁵ E⁶, evenly distributed over the floor of oven A, and thence through chimneys F² F³ F⁴ into the uptake x.

15 What I desire to claim and secure by Letters Patent is—

The lower chamber, B⁴, in combination with wall E³ and flues F F' and E E' E², substantially as and for the purpose specified.

ARTHUR SNOW.
